[57] **CLAIM**

The ornamental design for a drop cord light, substantially as shown and described.

DESCRIPTION

FIG. 1 is an isometric view from the top and side of a drop cord light showing my new design;

FIG. 2 is an isometric view from the top and opposite side thereof;

FIG. 3 is a front elevational view thereof on a reduced scale;

FIG. 4 is a side elevational view thereof on a reduced scale;

FIGS. 5 and 6 are respectively top and bottom plan views thereof on a reduced scale.
